UNITED STATES PATENT OFFICE.

WILLIAM LOREY AND JOHN BRAUN, OF PHILADELPHIA, PENNSYLVANIA.

LOOM SHUTTLE-BOX-OPERATING MECHANISM.

SPECIFICATION forming part of Letters Patent No. 352,419, dated November 9, 1886.

Application filed January 30, 1886. Serial No. 190,316. (No model.)

To all whom it may concern:

Be it known that we, WILLIAM LOREY and JOHN BRAUN, both citizens of the United States, residing in the city and county of Philadelphia, State of Pennsylvania, have invented a new and useful Improvement in Loom Shuttle-Box-Operating Mechanism, which improvement is fully set forth in the following specification and accompanying drawings, in which—
10 Figure 1 represents a plan or top view, partly broken away, of a loom having applied thereto an operating mechanism embodying our invention. Fig. 2 represents a cross-section thereof in the line $x-x$, Fig. 1, seen from the left-hand side. Fig. 3 represents a rear elevation of a portion of the loom, partly in longitudinal section in the line $y-y$, Fig. 1. Fig. 4 represents a section thereof in the line $z-z$, Fig. 1.
15 Similar letters of reference indicate corresponding parts in the several figures.

Our invention relates to mechanism for operating or adjusting the shuttle-box in relation to the pickers of a loom; and it consists of the novel features herein described, whereby 25 the regular alternation of the boxes or cells is effected with the greatest facility, and a positive adjustment of the shuttle-boxes is effected without liability of vertical play thereof in the throw of the lay.

30 Referring to the drawings, A designates the loom-frame, supporting the bearing for a main shaft, B, shafts C and D, and rock-shafts E F. Both shafts C and D are geared with the main shaft B by means of cog-wheels B' C' D', and 35 to the driving-shaft C is connected the oscillating lay or batten G by means of the usual cranks, C², and pitmen C³, while to the shaft D is connected a reciprocating slide, H, by means of a crank, D², and pitman D³, the relative angle or positions of the cranks being such that the motions of the lay and the slide 40 are in opposite directions. The rock-shaft E carries the lay G, while the rock-shaft F carries a releasing-lever, F', hereinafter referred 45 to, and is connected with the main shaft by means of arms F² and a rod, F³, to receive motion therefrom. The reciprocating slide H is fitted in guideways A' of the loom-frame, to move in a horizontal frame, and upon the slide 50 are two sets of cams or wipers, H' H² H³, for

alternately actuating a lever, J, and thereby operating a reciprocating rod, J', carrying the shuttle-boxes.

On the operating-lever J is mounted a head, L, having a series of vertical holes or passages, L' L² L³ L⁴, which are equal in number to the shuttle-boxes, and in which are fitted two pins or tappets, K K', one to each set of cams, for engaging the latter, the tappets moving or gravitating freely in said holes, which thus 55 constitute guides for the tappets, and also render the latter adjustable in relation to the cams. The cams H', &c., of each set are formed by the vertical edges of spirally-arranged steps or terraces, on which the tappets K K' rest in the 60 action of the cams thereon, as hereinafter described, and the top one of which is enlarged to furnish an extended support for the tappets, a space being left between the two sets of steps, at the converging ends of the cams, of sufficient 65 width to admit either of the tappets. Each set of cams or wipers H', &c., corresponds in shape with the other, and each occupies a reverse position to the other relatively to the line of motion of the cam-supporting 70 slide.

The tappets K K' are connected by means of cords K² to the outer ends of lifting-levers N, the inner ends or portions of which are in turn connected by means of cords N' to the respective 80 arms of the releasing-lever F', and to which inner ends of the lifting-levers are hung weights N², so that by the joint action of the releasing-lever and the weights the shifting-levers are operated to alternately release and lift the tappets. The lifting-levers N have their fulcra in 85 a pivot, N³, of a bracket, N⁴, which is a fixture of the loom-frame, and a cross-piece, N⁵, of which constitutes a stop for limiting the motion of the lifting-levers by the action of the 90 weights.

The operating-lever J is fulcrumed in a vertical pivot, O, to move like a cam-supporting slide, H, in a horizontal plane, and the tappets K K' are at one end of the lever, the other 95 end thereof being connected by means of a link, O', to a loose collar, O², of a reciprocating sleeve, P, which is fitted on the rock-shaft E, carrying the lay by means of a feather-key, E', so that the sleeve shares the motion of said 100

shaft together with the lay. The collar O^2 is fitted into a groove, P' , in the circumference of the sleeve, and hence the collar is adapted to shift the sleeve on the lay-shaft without 5 rocking. The reciprocating sleeve P is connected by means of a link, P^2 , to one arm of an elbow-lever, Q , which has its fulcrum in a pivot, Q' , on a bar, Q^2 , of the lay-frame, and the other arm of which is connected by means of 10 a link, Q^3 , to the box-supporting rod J' , so that a motion of the operating-lever is transmitted to said rod through the sleeve and the elbow-lever for adjusting the shuttle-boxes. The bar Q^2 of the lay-frame forms one of the guides 15 for the box-supporting rod J' , and the inner end thereof is united to an arm, Q^4 , on the lay-shaft.

The pivot O of the operating-lever J is fixed to the loom-frame, and to the upper end thereof 20 is arranged a spring, R , in form of a flat bar, which bears at the free end on a lip or shoulder, R' , of the lever-head L , so that by the frictional contact of said spring with the shoulder the operating-lever is steadied in its motion and held against accidental displacement. 25

For the purposes of explanation, let it be assumed that the lay is in its forward position, the operating-lever J having one of its tappets, as K , midway between the two sets of 30 cams, and the other, K' , in the line of motion of one set thereof, the rearward movement of the slide H , with its cams H' , &c., being completed. Now, in the throw of the lay backward the cam-supporting slide H moves forward, as indicated by the arrow in Fig. 1, the tappet K' is released, and the latter drops from step to step of the proper set of cams until said movement of the cam-supporting slide is completed, the operating-lever J in the meantime 40 remaining stationary. Then, when the lay returns to a front position, the cam-supporting slide H moves rearward, and the tappet K' is displaced by contact with the cam adjacent to the step on which it rests, whereby 45 the operating-lever J is forced in the direction of the arrow shown in Fig. 1, and the box-supporting rod J' is forced up to effect a proper adjustment of another cell of the shuttle-box. When the cam-supporting slide 50 H has completed its rearward movement, the tappets K K' are transposed in relation to the cams—that is to say, the tappet K is brought into the line of motion of the other set of cams, and is released in the forward movement of 55 the cam-supporting slide, so that when the latter again moves rearward said tappet K is displaced by one of the cams of the proper set, and the operating-lever is forced in a direction opposite to the arrow for readjusting the 60 shuttle-boxes. The coincident cams of the two sets correspond in effect on the operating-lever J , thereby rendering the motion of said lever equal in both directions, and the change of operation and adjustment of the cells of the 65 shuttle-box is effected by the different relative position of the tappets K K' as compared

with the cams, and is regulated by arranging in the said tappets in either adjacent or alternate holes, thereby bringing the said tappets in contact with different cams, the result of 70 which is to produce different adjustments of the shuttle-boxes, so that the order of succession of the shuttle-boxes may be regulated by that means. By the guide-holes L' , &c., of the lever-head the tappets K K' may be readily adjusted in the desired relation to the cams, 75 inasmuch as it is only necessary to place the tappets in one or the other of the holes.

It will be noticed that the motion imparted to the box-supporting rod J' is positive in both 80 directions, and hence a corresponding adjustment of the shuttle-boxes is effected, while, owing to the fact that the reciprocating sleeve P may rotate in its actuating collar, the rod, together with its boxes, is not liable to play 85 or move vertically in the throw of the lay, it remaining stationary.

Having thus described our invention, what we claim as new, and desire to secure by Letters Patent, is—

1. In a loom shuttle box-adjusting mechanism, a slide having two sets of stepped cams or wipers thereon and means, substantially as described, for reciprocating said slide, in combination with an oscillating lever having a perforated head, tappets fitted in perforations in said head, devices, substantially as described, for raising and lowering said tappets, a shuttle-box-carrying rod actuated by said lever, and devices connecting said rod to said lever, all substantially as and for the purpose set forth. 90

2. In a loom shuttle-box-adjusting mechanism, the frame A , having guideways A' , in combination with the reciprocating slide H , provided with two sets of stepped cams or wipers, each of said sets occupying a reverse position to the other relatively to the line of motion of the slide, means for actuating said slide, an oscillating lever having a head with 105 tappets, the latter having devices for raising and lowering the same in said head, and a shuttle-box-carrying rod, and devices connecting said rod with said lever, all substantially 110 as and for the purpose set forth. 115

3. The slide H , with cams thereon, and means, substantially as described, for operating said slide, in combination with the oscillating lever J , provided with a head carrying tappets, the shuttle-box-carrying rod, and devices connecting said lever to the shuttle-box-carrying rod, a releasing-lever, a rock-shaft carrying said releasing-lever, means for actuating said rock-shaft, and cords and levers connecting said levers to said tappets, all substantially as and for the purpose set forth. 120

4. In a loom shuttle-box-adjusting mechanism, a slide with two sets of cams, and means, substantially as described, for reciprocating the same, in combination with a lever having 130 a head with tappets, a rod carrying shuttle-boxes, devices connecting said lever to said

rod, a releasing-lever, a rock-shaft carrying said releasing-lever, lifting-levers, cords connecting said releasing-lever to said lifting-levers at the inner ends of the latter, cords connecting the outer ends of the said lifting-levers to the tappets, a main shaft and arms, and a rod connecting the rock-shaft to the main shaft, all substantially as and for the purpose set forth.

10 5. In a loom shuttle-box-adjusting mechanism, a slide having cams thereon and provided with means for reciprocating the same, in combination with an oscillating lever having tappets, a rod carrying the shuttle-boxes, devices for connecting said lever to said rod, a releasing-lever, a rock-shaft carrying the said lever, means for actuating said shaft, lifting-levers, cords connecting said lifting-levers to the tappets, and releasing-lever and weights connected to the inner ends of said lifting-levers, all substantially as and for the purpose set forth.

6. In a loom shuttle-box-adjusting mechanism, a reciprocating slide having cams thereon, and means for reciprocating said slide, in combination with the lever J, formed with the head L, tappets 'K K', the lay G, the rock-shaft E, having thereon the reciprocating sleeve P, the collar O', link O', the elbow-lever Q, the shuttle-boxes, the rod J', and links connecting said lever Q to the sleeve P and to the box-supporting rod J', respectively, all substantially as and for the purpose set forth.

7. In a loom shuttle-box-adjusting mechanism, the slide H, provided with two sets of

cams, and means for reciprocating said slide, in combination with the lever J, tappets K K', the rock-shaft E, the reciprocating sleeve P, mounted thereon, the rod J', carrying the shuttle-boxes, devices for connecting the sleeve P to the rod J', the lay G, the crank-shaft C, the pitmen, and the link and collar for connecting the lever J to said sleeve P, all substantially as and for the purpose set forth.

8. The slide H, provided with two sets of stepped cams, constructed substantially as described, and means for imparting reciprocating motion to the same, in combination with an oscillating lever provided with a perforated head having devices, substantially as described, for raising and lowering said tappets, a rod carrying the shuttle-boxes, devices for connecting said lever to said rod, and a spring bearing on said lever J and adapted to keep said tappets in contact with said cams, all substantially as and for the purpose set forth.

9. The lay and its rock-shaft, a reciprocating sleeve fitted on the rock-shaft and constructed with a loose collar, a box-supporting rod, an elbow-lever, links connecting the elbow-lever to the sleeve and rod, respectively, an operating-lever, means for actuating the same, and a link connecting the operating-lever to said collar of the sleeve, all combined substantially as and for the purpose set forth.
